[57] CLAIM

The ornamental design for a paddle wheel propelled
watercraft, as shown and described.

DESCRIPTION

FIG. 1 is a side elevational view of a paddle wheel
propelled watercraft showing my new design, the oppo-
site side view being a mirror image of that shown;
FIG. 2 is a top plan view thereof;
FIG. 3 is a front elevational view thereof;
FIG. 4 is a rear elevational view thereof;
FIG. 5 is a bottom plan view thereof;
FIG. 6 is a top perspective view thereof; and
FIG. 7 is a top perspective view thereof with decora-
tions applied thereto.

FIG. 1

FIG. 2

*FIG. 3**FIG. 4**FIG. 5*FIG. 6

FIG. 7
